UNITED STATES PATENT OFFICE

2,642,163

ARCH FORM FOR FURNACE ROOFS

Emmett E. McVey and James H. Opre,
Youngstown, Ohio

Application April 29, 1949, Serial No. 90,442

2 Claims. (Cl. 189—37)

1

The invention relates to collapsible forms for building masonry arches such as furnace roofs and the like.

Under present practice in rebuilding the arch roof of an open hearth or similar furnace, a wood form is first constructed, upon which the masonry arch is built. Twelve carpenters with twelve helpers require eight hours to build such a wood form and after the masonry arch is completed it requires the work of several men for several hours to tear down the wood form.

The present invention contemplates the provision of a prefabricated, collapsible form which may be erected in two hours by eight unskilled laborers, ready for building the masonry arch thereon, and which may be quickly and easily removed after the arch is built.

The object is to provide a form for the building of masonry arches such as furnace roofs and the like which is simple and inexpensive in construction and may be easily erected and torn down and which can be used repeatedly.

Another object is to provide such a form comprising a plurality of trussed forms, or centering members, each comprising an arcuate top chord of the curvature of the arch desired, an arcuate bottom chord of less curvature, radial struts between the chords, and bearing ends connecting the ends of the chords together.

A further object is to provide such a roof form in which the individual forms or centering members are of tubular construction.

A still further object is to provide such a roof form with spacers for detachably holding the several forms or centering members in position.

Another object is to provide an arch form of this character with wedge means for supporting the forms.

The above and other objects, apparent from the drawings and following description, may be attained, the above described difficulties overcome and the advantages and results obtained, by the construction, arrangement and combinations, and parts which comprise the present invention, a preferred embodiment of which, illustrative of the best mode in which applicant has contemplated applying the principle, being set forth in detail in the following description, and illustrated in the accompanying drawings, in which:

Figure 1 is an elevation of one of the forms or roof centers, showing the same in use for building an arch roof upon a furnace;

Fig. 2 a top plan view of a plurality of the cen-

ters or forms, connected in properly spaced relation for building an arch roof thereon;

Fig. 3 a fragmentary, perspective view of a plurality of the forms, with planks laid thereon, in position for building an arch furnace roof;

Fig. 4 an enlarged side elevation of one of the spacing members, with parts broken away for the purpose of illustration;

Fig. 5 an edge view of one of the spacers; and

Fig. 6 an enlarged, transverse section through one form or center, showing portions of two spacers connected thereto.

Referring now more particularly to the embodiment of the invention illustrated in the drawings, in which similar numerals refer to similar parts throughout the several views, the invention is shown as applied to the building of a roof for an open hearth furnace, although it should be understood that this is only for the purpose of illustrating an application of the invention, and that the improved arch form is adapted for the building of various types of masonry arches.

Portions of the conventional vertical, structural frame members of the furnace are indicated at 10, and the usual arch supporting plates carried thereby, are indicated at 11. These members do not form any part of the present invention but are illustrated to show the manner in which the improved arch forms or centers are used in constructing an arch roof in an open hearth furnace or the like.

Each individual form is in the shape of a truss, comprising the arcuate top chord 12, conforming to the curvature of the arch roof to be built, the curved bottom chord 13, having a considerably less curvature than the top chord and the substantially radial struts 14, which are welded or otherwise rigidly attached at their upper and lower ends to the top and bottom chords respectively as indicated at 15. These members are all preferably of tubular construction and may be made of standard pipe, shaped as best shown in Fig. 1.

Opposite ends of the top and bottom chords are welded or otherwise rigidly attached to the flat bearing plates 16, each of which has an upturned flange 17 at the adjacent end of the top chord 12.

In building the arch roof for an open hearth furnace, as shown in Figs. 1, 2 and 3, spaced tiers of bricks may be loosely laid up within each side of the furnace, adjacent to the framework as indicated at 18, and I-beams 19 may be horizontally supported thereon.

Spaced pairs of wedge blocks 20 may be placed upon the beams 19 to support opposite ends of the individual forms, the bearing plates 16 of the forms resting upon the corresponding wedge blocks, which are adjusted to properly position the ends of the forms adjacent to the arch supporting plates 11 of the furnace structure.

The individual forms are held in spaced relation by means of the spacers, indicated generally at 21. Each spacer may be in the form of a flat bar, as best shown in Figs. 4, 5 and 6, having a hook 22 at one end for engaging over the central strut 14 of one form and a U-shape portion 23 upon its other end for receiving the central strut 14 of the next adjacent form, as best shown in Figs. 2 and 6.

Staggered, relatively wide and narrow slots, 24 and 25 respectively, are formed in opposite sides of the hook 22 to receive a wedge 26 for tightly enclosing the strut 14 within the hook. Similar slots 27 and 28 are formed at opposite sides of the U-portion 23 for receiving a similar wedge 29 for wedging the central strut 14 of the next adjacent form within the U-shape portion of the spacer.

Preferably, as shown in Fig. 6, one spacer is connected to the lower end of each strut 14 while the other spacer is connected to the upper end thereof, so as to more rigidly hold the assembled forms in vertical position. The wedges 26 and 29 may be connected to the spacer 21 as by chains or other flexible members as indicated at 30.

Planks, as indicated at 31, are laid over the top chords of the plurality of spaced forms, as shown in Figs. 1 and 3, the upturned flanges 17 upon the end bearing plates of the forms preventing the planks from slipping down from the forms.

A masonry roof, of fire brick or the like, is then built upon the planks 31, as indicated at 32 in Fig. 1, the ends of the masonry arch being supported upon the arch supporting plates 11 of the furnace frame structure as shown in said figure.

When the arch roof is completed the wedge blocks 20 may be removed permitting the individual form members to drop down away from the arch so that the forms and planks may be removed.

According to the provisions of the patent statutes, we have explained the principle of our invention and described an embodiment thereof,

but we desire to have it understood that within the scope of the appended claims, the invention may be practiced otherwise than as specifically illustrated and described.

5 We claim:

1. A collapsible form for use in the construction of arches, comprising a plurality of similar forms, each comprising arcuate top and bottom chords and struts connected at opposite ends to the chords, spacers detachably connecting adjacent forms together, each spacer having a hook at one end engaging a strut of one form and an open U-shape portion at the other end engaging a strut of an adjacent form, there being slots in opposite sides of the hook and in opposite legs of the U-shape portion and wedges located through said slots and against said struts detachably connecting the spacers to the forms.

2. A collapsible form for use in the construction of arches, comprising a plurality of similar forms, each comprising arcuate top and bottom chords and struts connected at opposite ends to the chords, spacers detachably connecting adjacent forms together, each spacer having a hook at one end engaging a strut of one form and an open U-shape portion at the other end engaging a strut of an adjacent form, there being staggered, relatively wide and narrow slots in opposite sides of the hook and in opposite legs of the U-shape portion and wedges located through said slots and against said struts detachably connecting the spacers to the forms.

EMMETT E. MCVEY.

JAMES H. OPRE.
